UNITED STATES PATENT OFFICE.

ERNEST P. GARNER, OF CHARLOTTE, NORTH CAROLINA.

WINDOW SCREEN.

Application filed January 14, 1925. Serial No. 2,380.

To all whom it may concern:

Be it known that I, ERNEST P. GARNER, a citizen of the United States, residing at Charlotte, in the county of Mecklenburg and State of North Carolina, have invented new and useful Improvements in Window Screens, of which the following is a specification.

This invention relates to window screens and particularly to frames for this class of devices, and the primary object of the same is to provide a comparatively simple form of screen frame having the various parts or members thereof so associated as to be strong and durable and also effective in operation.

A further object of the invention is to provide means in connection with a window screen whereby the latter may be easily applied to have vertical sliding movement and readily removable for the purpose of repair.

The improved screen is provided with metal strips or members applied over the wire gauze or screen covering and secured to wooden members comprising the body of the frame by screws or analogous easily removable fastenings, the metal strips at the sides providing a neat finish and also contributing to the formation of grooves for engagement with the guide strips of the window frame, and the metal strip at the bottom providing for a lower rest means when the frame as a whole is lowered by extension thereof below the lower wooden strip of the body of the frame. The corners of the body frame of wood are materially strengthened by a novel construction which will be more fully hereinafter specified.

The improved form of screen frame is illustrated in the accompanying drawings, in which:—

Fig. 1 is a perspective view of the outer side of a window organization, showing the improved screen frame and screen applied thereto.

Fig. 2 is an enlarged side elevation of outer portions of the window frame and improved screen frame broken away and showing the screen frame and screen in lowered position and also illustrating a frictional retaining spring means carried by part of the window frame.

Fig. 3 is a horizontal section taken on the line 3—3, Fig. 2.

Fig. 4 is a transverse vertical section taken on the line 4—4, Fig. 2.

Fig. 5 is a sectional perspective view, particularly showing the bottom corner structure and lower metal strip embodying the essential features of the invention.

Fig. 6 is a detail perspective view of one of the upper corner portions of the improved frame.

Fig. 7 is an enlarged transverse vertical section through the window frame, sash and screen, showing the manner of applying or removing the screen.

Fig. 8 is an outside elevation of a portion of a window frame, showing the improved screen in place, and the manner of resetting the slide strips or guides illustrated in dotted lines.

The improved window screen frame comprises upright side bars 5 and upper and lower horizontal bars 6 and 7. The upper horizontal bar and the upper ends of the side bars 5 are secured in a very novel manner, each end of the bar 6 having a series of slots or grooves 8 formed therein to receive tongues 9 and 10 of the side bar, the innermost slot or groove 8 opening through the inner side of the bar 6 and the latter formed at the inner side with an outwardly projecting tongue 11, which is materially longer than the tongues 9. The strip 5 is also formed at its upper end with an inner slot or seat 12, to receive the tongue 11 in flush relation thereto. The tongue 10 of the strip 5 is of the same dimensions as the tongue 12, and when the ends of the bars 5 and 6 are interfitted to form the corner jointure, the tongues 10 and 11 project as a double wall or thickness of material inwardly beyond the terminals of the tongues 9. The tongues 9, 10 and 11 are firmly secured by the application thereto of waterproof glue or analogous cementitious material, or otherwise secured as desired, and by the formation of the parts as just explained, a strong corner structure is provided. The corner or end connections between the lower horizontal bar 7 and the side or upright bars 5 are also advantageous, the bar 7 at each end being formed with tongues 13, which are fitted and secured in slots or grooves 14 opening through the lower end of the adjacent bar 5. The slots or grooves 14 are of such depth as to permit the tongues 13 to be moved upwardly a considerable distance above the lower ends

or terminals of the bars 5, the grooves 14 providing depending tongues 15 as parts of each bar 5 at the lower ends of the latter, as clearly shown by Fig. 5. The tongues 5 13 at the ends of the lower horizontal bars 7 are also secured in the slots or grooves 14 by suitable water-proof glue or other cementitious material. After the corners of the upper and lower horizontal bars 6 and 10 7 are assembled and secured by glue or analogous material as just explained, they will be further secured by nails or pins driven therethrough, to insure a strong and durable connection at the corners of the 15 body members of the frame. By providing a number of tongues and grooves as specified, a greater surface for the application of glue is obtained and the nails or pins will be more effective in holding the corners 20 when there is a strain on the frame. The tongues are so spaced that at least a portion thereof, or one at each corner, will pass the slot, groove or rabbet structure and reinforce the inside edge or lip side of the screen 25 and thereby render the said lip less liable to split off and add materially to the strength of the frame as a whole.

Applied over the body frame as just explained, and which is preferably made of wood, are side metal strips 16 and upper and lower metal strips 17 and 18. These metal strips are applied to the outer sides of the body members of the frame and the side strips 16 have their edges bent outwardly 30 at right angles, as at 19, to stiffen or reinforce the same, and the upper edge of the strip 17 is formed with an inwardly bent angular flange 20, which snugly fits over a portion of the upper edge of the upper 35 horizontal bar 6. The lower edge of the top metal strip 17 is bent outwardly at right angles, as at 21, to reinforce or stiffen the same, and the lower metal strip 18 has an upper outwardly bent right-angular stiffening flange 22 and a lower inwardly projecting right-angular flange 23, which forms 40 a bottom rest to engage the sill and may be of varying width as found necessary. The lower ends of a portion of the downwardly 45 projecting tongues 15 of the side bars 5 contact with the opposite extremities of the flange 23. These metal strips 16, 17 and 18 are applied over the wire gauze 24, screws 50 25 being inserted at intervals, as shown by Fig. 2, to hold these strips in place and likewise to engage the wire gauze. It is preferred that the holes in the metal strips through which the screws 25 extend be punched or formed after the strips are laid 55 against or over the wire gauze 24, so as to cause the burrs formed by punching the metal to engage the wire gauze and be pressed into the wood of the bars of the body frame, to more securely hold the metal 60 strips in place and also positively fasten the

wire gauze, this incidental securing feature by formation of the burrs being particularly effective. At the sides of the screen frame the metal strips 16 project sidewise outwardly beyond the terminals of the slots or 70 grooves 8 and tongues 9 and in line with the outer edges of the upright side bars 5, and by this means together with the provision of the projecting tongue structure 10 and 11, a reinforced groove means is provided at each side of the screen. The flange 20 projecting inwardly from the upper portion of the upper strip 17 covers the upper edge of the wire gauze and shields and hides the latter. The lower metal strip 18 with its bottom supporting flange 23 and its upper flange 22 forms a very efficient reinforce 75 structure at the bottom of the frame and also forms an inner opening for insertion of the fingers of an operator, and thereby efficient means is provided for conveniently raising and lowering the screen. The lower flange 23 may be bent in various shapes to conform to the surface contour of the window sill against which it is adapted to bear. The outer metal side strips 16, forming one wall for each of the side grooves of the screen, are of material advantage in view of the yielding character or flexibility of the metal against the means for guiding the screen when the latter is mounted in the window frame. Dampness will not in the least affect these metal strips forming outer walls for the grooves and there will be no liability of jamming or stretching of the screen on the guide means as is often the case with screens having all wood sides or side members. The upper and lower outer metal strips also add materially to the 90 rigidity of the screen frame as a whole and provide for a more positive securing of the upper and lower edge portions of the wire gauze or screen fabric 24 than is possible by the use of wooden strips.

To facilitate the application of the screen to a window frame, the stops or guides 26 of the side members 27 of the frame are formed in two sections 28 and 28^a, which are respectively fixed and movable, joints being provided between the ends of the said sections, or each section 28 has longitudinal slots and tongues 29 at the upper end thereof, to receive spaced tongues 30 at the lower end of each section 28^a. Each section 28^a is fastened at its upper extremity and is operable to swing outwardly after the lower tongues 30 have been separated or pulled out from the slots and tongues 29, said operation being accomplished by first pulling or pressing each section 28^a inwardly in a sidewise direction relatively to the window frame, as shown in dotted lines by Fig. 8. Owing to the length of the upper sections 28^a, the sidewise inward bending or pressing stress exerted thereon will cause the said 110 115 120 125 130

sections to yield sufficiently to separate the same from the lower sections 28. After the sections 28^a have been separated as just explained and moved outwardly as shown in 5 full lines by Fig. 7, the screen frame is moved upwardly thereover far enough to clear the lower extremities of the sections 28^a and the said latter sections are then pushed forwardly into normal position and 10 the lower extremities of the sections 28^a bent inwardly in a sidewise direction, to assemble the ends of the same with the upper ends of the sections 28, and by this means the stops or guides 26 will be held 15 in normal straight position and the screen will be free to move upwardly and downwardly thereover without obstruction in view of the close fitting of the jointed ends by means of the slots and tongues 29 and 20 30. At one side at least the upper portion of one of the sections 28^a has a friction spring 31 secured thereto for engagement by one side of the screen frame to hold the screen elevated when it is desired to have a 25 clear opening through the lower portion of the window frame, or in the event it is desired to close the lower sash and open the upper sash.

It is not always necessary to use cementitious material or glue in securing the corner joints, as the tongues, slots or grooves have such a close fitting that they may be tightly held against loose movement or disjointure by nails, pins or other fastenings inserted 30 therein.

The improved screen frame as a whole will be found exceptionally convenient and advantageous as compared to the ordinary well known screen constructions, and it is 40 proposed to modify the proportions, dimensions and minor details of construction as desired and found necessary to adapt the improved screen structure to various sizes of window frames and sash.

45 What is claimed as new is:

1. A screen frame comprising upper and lower and side main frame members having corner joints comprising interfitted and secured tongues and slots, a part of the 50 tongues being projected beyond the remaining portion of the tongues and providing reinforcing means and the side members of the frames also extending beyond the ends of the upper and lower members, a wire gauze covering applied to the main frame members, and metal strips removably applied over the wire gauze covering and the one side of the main frame members and having flanged edges to reinforce the same, 55 the side metal strips projecting outwardly beyond the ends of the upper and lower main frame members equally with the side members of the main frame to form grooves for engaging guide devices.

60 65 2. A screen frame comprising upper and

lower and side main frame members having corner joints comprising interfitted and secured tongues and slots, a part of the tongues being projected beyond the remaining portion of the tongues and providing 70 reinforcing means and the side members of the frame also extending beyond the ends of the upper and lower members, a wire gauze covering applied to the main frame members, and metal strips removably applied over the wire gauze covering and the one side of the main frame members and having flanged edges to reinforce the same, the side metal strips projecting outwardly beyond the ends of the upper and 80 lower main frame members equally with the side members of the main frame to form grooves for engaging guide devices, the lower metal strip having an upper outwardly projecting terminal angular flange and a lower inwardly bent angular flange to engage a window sill.

3. A screen frame comprising upper, lower and side main frame members secured at their corners, the side members projecting outwardly beyond the ends of the upper and lower members, a wire gauze screen applied to the main frame members, and metal plates removably secured to the upper and lower and side main frame members over the wire gauze, the side plates forming with the outwardly projecting portions of the main side members grooves for engagement with guide means and the upper metal strip having the upper edge thereof 90 bent over a portion of the upper edge of the upper main frame member and its lower edge bent outwardly.

4. A screen frame comprising upper, lower and side main frame members secured at their corners, the side members projecting outwardly beyond the ends of the upper and lower members, a wire gauze screen applied to the main frame members, and metal plates removably secured to the upper and lower and side main frame members over the wire gauze, the side plates forming with the outwardly projecting portions of the main side members grooves for engagement 100 with guide means and the upper metal strip having the upper edge thereof bent over a portion of the upper edge of the upper main frame member and its lower edge bent outwardly, the lower metal strip having an outwardly extending flange at its upper edge and a lower inwardly bent flange to engage a window sill and spaced from the adjacent frame member for insertion of the fingers of an operator, the upper flange of the lower metal strip also serving as a means for raising and lowering the screen and the lower flange of the lower metal strip also serving as a reinforcing means for portions of the lower corner joint means.

5. A screen frame comprising upper, lower 130

and side main frame members secured at their corners, the side members projecting outwardly beyond the ends of the upper and lower members, a wire gauze screen applied to the main frame members, and metal plates removably secured to the upper, lower and side main frame members over the wire gauze, the side plates forming with the outwardly projecting side portions of the main side members grooves for engagement

with guide means and the lower metal plate having the lower edge bent inwardly to engage a window sill and spaced from the adjacent lower frame member to form an open means for insertion of the fingers of 15 the hand of an operator to raise and lower the screen.

In testimony whereof I have hereunto set my hand.

ERNEST P. GARNER.
